FIG. 2

FIG. 3

FIG. 4

FIG. 5

FIG. 6

FIG. 7

FIG. 1 is a perspective view of the rectifier unit for electric shavers, showing my novel design;

FIG. 2 is a side elevation view thereof;

FIG. 3 is a side elevation view thereof showing the opposite side to that shown in FIG. 2;

FIG. 4 is an end elevation view thereof;

FIG. 5 is an end elevation view thereof showing the opposite end to that shown in FIG. 4; and

FIG. 6 is a bottom plan view thereof; and

FIG. 7 is a top plan view of the recessed cover plate.

The characteristic feature of my design resides in the contrast between the recessed cover plate in combination with the rectifier housing as best illustrated in FIGS. 2, 4 and 6 on the drawing.

I claim:

The ornamental design for a rectifier unit for electric shavers, as shown and described.
